DESIGN FOR A HAT

Adolph Reinsberg, Chicago, Ill.

Application July 20, 1944, Serial No. 114,483

Term of patent 3½ years

(Cl. D3—13)

To all whom it may concern:

Be it known that I, Adolph Reinsberg, a citizen of the United States of America, residing in Chicago, county of Cook, and State of Illinois, have invented a new, original, and ornamental Design for a Hat, of which the following is a specification, reference being had to the accompanying drawing, forming part thereof.

Fig. 1 is a rear perspective view of a hat showing my new design.

Fig. 2 is a rear perspective view of the hat shown in Fig. 1 with the rear flap in lowered position and the front brim turned down.

Fig. 3 is a front perspective view of the hat shown in Figure 1.

I claim:

The ornamental design for a hat, substantially as shown.

ADOLPH REINSBERG.
